UNITED STATES PATENT OFFICE.

CHRISTIAN YAUCH, OF DETROIT, MICHIGAN.

SKYLIGHT.

1,368,531.

Specification of Letters Patent. Patented Feb. 15, 1921.

Application filed October 27, 1919. Serial No. 333,460.

To all whom it may concern:

Be it known that I, CHRISTIAN YAUCH, a citizen of the United States, residing at Detroit, in the county of Wayne and State of Michigan, have invented certain new and useful Improvements in Skylights, of which the following is a specification.

This invention relate to a skylight construction, and has for its object a skylight 10 in which the astragal and the astragal cap are assembled by a new form of fastening that not only makes the assembly easy but serves to press the packing yieldably upon the glass and hold the glass panes.

15 In the drawings,—

Figure 1 is a cross section of a skylight longitudinally of the astragal.

Fig. 2 is a section on the line 2—2 of Fig. 1.

20 Fig. 3 is a sectional detail taken along the section line 3—3 of Fig. 2.

Fig. 4 is an end view of the astragal-supporting cradle.

25 Fig. 5 is a perspective of the astragal-supporting cradle.

Fig. 6 is an enlarged fragmentary section, being a left fragment of the same section that is shown in Fig. 1.

30 Fig. 7 is a similar enlarged fragmentary section, being a right fragment of the section shown in Fig. 1.

Fig. 8 is a large fragmentary section, being one of the intermediate sections shown in Fig. 1.

35 Fig. 9 is a perspective of the saddle used to support the upper end of the astragal.

Fig. 10 is a perspective of one end of the packing for the overlapping panes.

40 *a* designates the astragal, which is of inverted T shape in cross section to form not only gutters but also a support for the glass panes *b*. This astragal is offset 1 for each cross row of panes to compensate for the overlapping of the panes and is offset at its

45 lower end (Fig. 6) to provide room for the flashing *x* to be turned up to form the gutter *y*. The astragal is provided at the points *c* with bayonet slots *d*. The usual sheet metal cap strip *e* is provided with perforations

50 through which may be slipped the cotter pins *f*. This enables the spring metal cap strip *e* to be forced down upon the packing *g* upon the glass to force the cotter pin *f* in the mouth of the bayonet slot *d*. It may

55 then be slid into the back of the bayonet slot *d*. The spring action afforded by the

slight distortion of the spring metal cap *e* not only serves to hold the cotter pin in the bayonet slot but it further serves to securely hold the packing *g* in place. The 60 ends of the cap strip *e* are turned down and shaped as at *Z* to form a depending shoulder as shown in Fig. 8 to hold the glass panes. Hence no other glass retainer is required and the weight of the glass assists in 65 holding the cap strip *e* cotter pins in the bayonet slots. This bayonet slot *d* form of fastening may very readily be applied.

In Figs. 4 and 5, I have shown a cradle for supporting the end of the astragal and 70 allowing expansion of that member. This cradle comprises a single casting forming a base *h*, an upright end *i* and a pair of hooked flanges or lips *j* spaced and shaped so as to form a recess *k* nicely calculated to fit over 75 the gutters of the astragal. The base *h* is slotted as at *l* to receive bolts. The saddle *m* comprises a base *o* that may be bolted to a portion of the ridge bar 2 or other support while the hooked flanges or lips *p* are like 80 the similar members *j* and *k* of the cradle shaped to receive the gutters of the astragal *a* and in expanding and contracting the astragal *a* is free to slide through the saddle and cradle.

85 It will be noted that the end upright *i* of the cradle is provided with a pair of openings *n*. These are ventilation ports to allow a slight amount of ventilation on the under side of the skylight to prevent condensation. 90

The transverse packing *s* is a folded strip of distortable material with a wire *t* that has its ends bent into legs *u* which can be hooked into the ends of the packing strips *g* to hold the cross packing *g* in place (compare Figs. 95 8, 10 and 2.)

What I claim is:

1. In a skylight construction, the combination of an astragal, glass panes supported upon the astragal, upright packing strips 100 lying on the top of the glass panes along the astragal, cap strips, means for securing the cap strips tightly to the astragal and holding the upright packing strips in place, and cross packing strips for lying between the 105 overlapped panes, said cross strips having each a wire passing therethrough and formed into legs at the ends, which legs hook into the adjacent upright packing strips.

2. In a skylight construction, the combination of an astragal provided with bayonet slots in its upper side, a glass pane supported 110

upon the astragal, packing lying on the top of the glass pane, distortable cap strips provided with edge portions adapted to be spread, and loosely restrained pins running from side to side of the cap strips, said cap strips being capable of assembly upon the astragal by pressing the same down to spread the edge portions thereof and engage the said pins in the offsets of the bayonet slots in which they are held by the yielding pressure afforded by the spread edges of the cap strips.

3. In a skylight construction, the combination of an astragal provided with bayonet slots in its upper side, panes of glass sup-

ported upon the astragal, a spring metal distortable cap strip provided with yieldably spreadable edge portions, and loosely restrained pins reaching from side to side of the cap strip near the top thereof, the said cap strip being assembled upon the astragal and into contact with the glass by pressing the same down, thereby causing the edge portions to yieldably spread and engaging the pins in the bayonet slots whereby the bayonet lock and the yielding of the side edges of the strip serve to tighten the fit between the strip and the glass.

In testimony whereof I affix my signature.
CHRISTIAN YAUCH.
